UNITED STATES PATENT OFFICE.

WILLIAM P. BETTENDORF, OF DAVENPORT, IOWA.

CAR-BOLSTER.

SPECIFICATION forming part of Letters Patent No. 700,402, dated May 20, 1902.

Application filed November 25, 1901. Serial No. 83,610. (No model.)

To all whom it may concern:

Be it known that I, WILLIAM P. BETTENDORF, a citizen of the United States, and a resident of Davenport, in the county of Scott 5 and State of Iowa, have invented certain new and useful Improvements in Bolsters for Cars, of which the following is a full, clear, and exact specification.

The object of my invention is to provide a 10 tubular bolster for cars, the body of which is made of one piece of metal suitably pressed into shape and combining in a very economical form of structure both durability and lightness. This I accomplish by the means 15 hereinafter fully described and as particularly pointed out in the claims.

In the drawings, Figure 1 illustrates the blank or templet from which my invention is formed, one half of the length of said figure 20 illustrating a templet for one style of bolster and the other half another style. Fig. 2 is a plan view of a bolster, one half the length thereof illustrating one style of bolster and the other half another style thereof. Fig. 3 25 is a side view of the same. Fig. 4 is a longitudinal section therethrough, showing the ends thereof supported by one style of springs at one end and another style at the other end. Fig. 5 is a view of the right-hand end of the 30 bolster. Fig. 6 is a cross-section taken on dotted line 6 6, Fig. 4.

Referring to the drawings, A represents the blank from which my invention is formed. The left-hand end portion of the blank shown 35 in Fig. 1 comprises a sheet-metal plate the length of which corresponds to the length of the completed bolster and the width twice that of the completed bolster plus twice the depth of the sides thereof. The style of the bolster 40 shown in the drawings has a truss shape—that is, its upper side is, barring the central bearing-plate and the side bearings, all on the same plane from end to end, and its depth is greatest at its center of length and inclines 45 upward from its center toward its ends, where its upper and lower sides are parallel for a short distance to provide a horizontal bearing for the upper spring-plate. The blank, therefore, is widest at its center of length a, 50 and its side edges b, extending from the said center of length toward the ends of said blank, converge toward each other at a correspond-

ing angle until the portions of the ends c of the blank are reached which are to be formed into the end portions of the bolster having 55 parallel upper and lower sides, whereupon said side edges extend parallel to each other for the remainder of their length.

In the right-hand portion of the blank shown in Fig. 1 the side edges of the end portion are 60 provided with corresponding laterally-projecting ears d instead of being parallel to each other, as hereinbefore described.

In forming the bolster B (shown in the left-hand portion of the several figures of the 65 drawings) the blank is pressed so that the width of the bolster is the same throughout its entire length and its depth is as hereinbefore specified. Heretofore the centrally-located bearing-plate of the bolster consisted 70 of a separate casting or pressed-metal plate secured by rivets or bolts in position, and this was likewise the case with regard to the side bearings and the guide-plates. In my invention the central bearing-plate C is pressed 75 into shape out of material of the blank during the operation of converting the blank into the bolster, and so likewise are the side bearings D D and the guide-plates E E. The bolster may be formed with either or all of these 80 integral accessories omitted, however, and said parts may be separately made and secured in place in the usual manner. When the blank has been pressed into shape, the longitudinal side edges of said blank are 85 brought together and welded or otherwise united together. I prefer to have said edges meet at a plane midway between its sides; but of course they could be brought together at some other point and answer substantially 90 as well. When the edges of the blank are thus brought together, a tubular bolster is formed, which is less in weight than any bolster known to me and is both strong and durable.

The form of bolster shown in the right-hand half of the first four figures of the drawings is made the same as that hereinbefore described, and what has heretofore been said will apply to the latter as well as to the former, except as regards the construction of the ends of the bolster. The bolster is formed so that the ears d d of the blank will extend 95 downward from either side of the ends of the

bolster parallel to each other and in the same planes as the longitudinal sides of said bolster to form retaining walls or shields k , between which the peculiar roller truck-springs K (shown in Fig. 4 of the drawings) can be placed. In order to provide a bearing for the upper end of the springs K , I employ an end plate I , which is of suitable oblong proportions and has one end secured to the under side of the bolster at a point back of the shields about where it commences to incline downward. From this point the said plate extends between said shields, to which its side edges are suitably secured, if desired, to the end of the bolster, and then extends upward to and laps over and is secured to the upper surface of said bolster, substantially as shown. Other means for providing a bearing for said springs K may be provided, however, if desired.

What I claim as new is—

1. A tubular bolster, consisting of one piece of sheet metal the longitudinal edges of which are united together.
2. A car-bolster comprising a structure tubular throughout its entire length, consisting of one piece of sheet metal the longitudinal edges of which abut and are united together.
3. A car-bolster comprising a structure made of a single plate of sheet metal, tubular throughout its entire length, the longitudinal edges of which are united together.
4. A car-bolster comprising a truss-shape structure, tubular throughout its entire length, consisting of a single piece of sheet metal the longitudinal edges of which abut and are united together.
5. A car-bolster comprising a structure, tubular throughout its entire length, consisting of a single piece of sheet metal the longitudinal edges of which are brought in contact and united together and having the central bearing-plate thereof made integral therewith.
6. A car-bolster comprising a structure made of a single plate of sheet metal the longitudinal edges of which are brought in contact and united together and tubular throughout its entire length, and having a central bearing-plate pressed from and made integral therewith.
7. A car-bolster comprising a structure, tubular throughout its entire length consisting of a single piece of sheet metal the longitudinal edges of which are brought in contact and united together and having the side bearings made integral therewith.

8. A car-bolster comprising a structure made of a single plate of sheet metal the longitudinal edges of which are brought in contact and united together and tubular throughout its entire length, and having side bearings pressed from and made integral therewith. 60

9. A car-bolster comprising a structure, tubular throughout its entire length consisting of a single plate of sheet metal the longitudinal edges of which are brought in contact and united together and having the truck-column guides thereof made integral therewith. 65

10. A car-bolster comprising a structure made of a single plate of sheet metal, the longitudinal edges of which are brought in contact and united together and tubular throughout its entire length, and having a truck-column guide pressed from and made integral therewith. 70 75

11. A car-bolster comprising a structure tubular throughout its entire length, consisting of a single plate of sheet metal having the longitudinal edges thereof brought in contact and united together and having the central bearing-plate, the side bearings, and the truck-column guides thereof made integral therewith. 80

12. A car-bolster comprising a structure made of a single plate of sheet metal, the longitudinal edges of which are brought in contact and secured together and tubular throughout its entire length, and having a central bearing-plate, side bearings and truck-column guides pressed from and made integral therewith. 85 90

13. A car-bolster comprising a truss-shape structure, tubular throughout its entire length consisting of a single plate of sheet metal the longitudinal edges of which are brought in contact and united together and having the central bearing-plate the side bearings, and the truck-column guides thereof made integral therewith. 95 100

14. A car-bolster comprising a truss-shape structure, made of a single plate of sheet metal the longitudinal edges of which are brought in contact and united together and tubular throughout its entire length, and having a central bearing-plate, side bearings, and truck-column guides pressed from and made integral therewith. 105
